J. SAWDON

DUPLEX MAILING ENVELOPE

Filed March 6, 1923

Inventor:

Joseph Sawdon

by Arthur F. Durand, Atty.

UNITED STATES PATENT OFFICE.

JOSEPH SAWDON, OF QUINCY, ILLINOIS, ASSIGNOR TO DU-PLEX ENVELOPE CORPORATION, OF QUINCY, ILLINOIS, A CORPORATION OF ILLINOIS.

DUPLEX MAILING ENVELOPE.

Application filed March 6, 1923. Serial No. 623,095.

To all whom it may concern:

Be it known that I, JOSEPH SAWDON, a citizen of the United States, and resident of Quincy, Adams County, Illinois, have invented a certain new and useful Improvement in Duplex Mailing Envelopes, of which the following is a specification.

This invention relates to duplex mailing envelopes of the kind in which a relatively large compartment is provided for printed matter or other matter less than first class, and in which a smaller compartment is provided for other matter, all in one unitary envelope.

Generally stated, the object of the invention is to provide a novel and improved construction whereby the smaller compartment, although sealed on the face of the envelope, is nevertheless accessible at some other point, preferably inside of the envelope, so that when printed form letters, or other matter less than first class, are enclosed in said smaller compartment, the contents of both compartments are accessible for the purpose of inspection by the postoffice officials, in a manner that will comply with the rules of the department.

It is also an object to provide certain details of construction and combinations tending to increase the general efficiency and the desirability of a duplex mailing envelope of this particular character.

To these and other useful ends the invention consists in matters hereinafter set forth and claimed and shown in the accompanying drawings in which—

Figure 1 is a plan view of one of the blanks from which the body or larger compartment of the envelope is made, showing the inside surface thereof.

Figure 2 is a plan of the blank which forms the inner wall of the smaller compartment.

Figure 3 is a face view, or a view showing the address side, which is ordinarily regarded as the front side of an envelope, but on a larger scale, of a duplex envelope embodying the principles of the invention.

Figure 4 is an enlarged horizontal section on line 4—4 in Figure 3.

Figure 5 is an enlarged vertical section on line 5—5 of Figure 3.

Figure 6 is a view similar to Figure 5, showing another form of the invention.

As thus illustrated, the body of the envelope, and the larger compartment thereof, are formed from the blank shown in Figure 1, which comprises the front wall 1, the flaps 2 and 3 which, when fastened, together form the back wall of the envelope, and also the end flaps 4 and 5, the latter being folded over upon the flaps 2 and 3 to close and seal one end of the envelope. The flap 4 is preferably merely tucked inside the end of the envelope, after the printed matter or other matter less than first class is inserted in the larger compartment thus formed. The front wall 1 is provided with a slot 6 so shaped that a flap 7 is provided, and the front wall is also provided with an outlook portion 8 to expose the address on the printed form letter, or other matter, which may be inserted in the smaller compartment. Of course, the outlook feature can be omitted and the address placed on the envelope in the ordinary manner. This smaller compartment is formed from the blank shown in Figure 2, this blank having its upper portion glued to the flap 7 at 9, as shown more clearly in Figure 5, after inserting the flap 10 upwardly through the slot 6 previously mentioned. This flap 10 is gummed and when turned down as shown in Figure 5 can be secured to the front wall 1 of the envelope, as shown in Figure 3, thereby to seal the top of the smaller compartment 11 which is formed between the front wall 1 and the body portion 12 of the smaller blank. It will be seen, however, that this pocket 11 is open at the lower edge thereof, and at one or both ends, (the end adjacent the flap 5 may be glued to the inner surface of the front wall 1, by a gummed surface, as indicated by the vertical dotted line at the right in Fig. 2) so that the post office inspectors can pull out the flap 4 and thus have access to both the large compartment 13 and the said smaller compartment 11, in a manner that will be readily understood. At the same time, however, the smaller compartment shows on the face of the envelope as being sealed, and the flap 10 is preferably provided with means 14 to attract the attention of the person receiving the envelope, to indicate the relative importance of the matter enclosed in the small compartment. On the face of the large compartment, preferably at the upper right hand

corner thereof, a space 15 is provided for postage sufficient to cover the entire contents of the envelope. The smaller compartment is preferably outlined on the 5 front of the envelope, as by a black line 16, or by any suitable means.

As shown in Figure 6, the smaller compartment 11 is sealed at its lower edge at 17 and it may also be sealed at one end, but 10 left open at the other end, adjacent the flap 4, as previously described, so that the contents of both compartments may be inspected by the postoffice officials.

From the foregoing it will be seen that a 15 duplex envelope is provided having a relatively large compartment for anything which may be sent through the mails, and having a smaller compartment for a form letter, or for something else of relatively 20 greater importance than the contents of the larger compartment, or which for some reason it is desired to segregate from the contents of the large compartment. Thus the smaller compartment and its contents 25 attract the attention of the person receiving the envelope, in the desired manner, but at the same time the entire contents of the envelope are subject to postage less than first class, in view of the fact that both compartments are open so that the contents of each compartment are subject to inspection, and hence only things which are subject to 30 less than first class postage are enclosed in the envelope for transmission through the 35 mails.

In practice the outside surface of the flap 4 may have the words "For postal inspection of smaller compartment, pull out this flap" printed thereon, in such a manner that 40 an inspector will know how to obtain access to the contents of the smaller compartment, notwithstanding that this smaller compartment has the appearance of being sealed on the face or address side of the envelope 45 as a whole. Also, the back of the envelope may have printed thereon the words "See important enclosure on other side", and in this way the duplex character of the envelope is made noticeable and conspicuous. 50 The contents of the two compartments may be subject to the same rate of postage, but at the same time they are segregated in separate compartments and the contents of the smaller compartment are, to the general 55 public, apparently sealed up, just as a first class letter would be, but the postoffice employees understand and know how to inspect the contents of both compartments.

It will be seen that the smaller compartment, by reason of the flap 10, not only simulates the appearance of being sealed, but also is in fact entirely sealed on the face or address side of the envelope. In other words, when the flap 10 is sealed, the smaller 65 compartment is then inaccessible anywhere

on the face or front of the envelope, and the face or front of an envelope is, of course, the side upon which the address is placed. Nevertheless, notwithstanding the actual sealing of the smaller compartment everywhere on the address side of the envelope, both compartments are accessible for inspection of the contents thereof, and inspection of each compartment is controlled or permitted or afforded by the loose flap 4, 75 this single flap being common to the two compartments in this respect.

Thus there is a plurality of compartments, and one compartment has the appearance of having been left open to receive its 80 contents on the face or address side of the envelope, and of having been finally sealed on the face or address side of the envelope, when ready to be deposited in the mails. Before the envelope is used, the one compartment, therefore, is open at two points, for it is not only open inside the envelope, as explained, but is also open on the face or address side of the envelope. When the envelope is received by the addressee, the 85 smaller compartment has the appearance on the face of the envelope of having been open to receive its contents and thereafter sealed. The addressee may not notice the fact that the smaller compartment is open inside, but 90 this is not important, for the intent and purpose is to merely leave all compartments open for inspection of the contents thereof by the postoffice employees. The envelopes 95 can be sold to the users with the smaller 100 compartment either open or closed, on the face or address side of the envelope, inasmuch as the flap 10 can be sealed by the manufacturer, or by the user. In any event, when the envelope reaches the addressee, the 105 flap 10 in reality merely simulates means for sealing the small compartment, or means for opening the small compartment, for while having the appearance of being sealed the small compartment is in reality unsealed and 110 is open, so that its contents may be inspected in the manner explained. Thus a letter placed in the smaller compartment has the attractive and otherwise useful appearance 115 of being sealed, while being transmitted through the mails, but may in reality be merely a printed or form letter which, under the rules of the postoffice, must be left open for inspection.

What I claim as my invention is—

1. A duplex mailing envelope comprising, when ready to be deposited in the mails, a plurality of compartments all of which are open for inspection of the contents thereof, having a loose flap affording access to all 125 of said compartments, and means outside to give one compartment the appearance of having been open to receive its contents and thereafter sealed.

2. A duplex mailing envelope comprising,

when ready to be deposited in the mails, a plurality of compartments one of which has the appearance on the address side of the envelope of having been open to receive the 5 contents and thereafter sealed, and is in fact entirely sealed on the address side, but all of which compartments are open for inspection of the contents thereof.

3. An envelope structure as specified in 10 claim 2, said compartment which has the appearance of being sealed on the face of the envelope being open at an edge thereof inside of the envelope.

4. An envelope structure as specified in 15 claim 2, said compartment which has the appearance of being sealed being smaller than the other compartment, and the smaller compartment being located on the address side of the envelope, said smaller compartment having a sealing flap for its upper edge, which flap gives the smaller compartment the appearance of being entirely sealed, and an address space being below said flap.

25 5. An envelope structure as specified in claim 2, said apparently sealed compartment being located on the address side of the envelope, with a place for the address within the area of the apparently sealed compartment, and the envelope having a loose flap at one end which can be pulled out to afford access to the apparently sealed compartment.

6. An envelope structure as specified in 25 claim 2, said apparently sealed compartment being smaller than the other compartment, and this smaller compartment being formed by the front wall of the envelope and by a smaller inner wall, so that the smaller compartment is within the area of the larger compartment, and having a flap on the front of the envelope to give said smaller compartment the appearance of being sealed, with the place for the address below said flap, and means at one end of the envelope 40 to afford access to both compartments, so that matter less than first class may be enclosed in each compartment.

45 7. The improved duplex mailing envelope having a relatively large and a relatively small compartment, one within the area of the other, and means comprising a single loose flap whereby the contents of each compartment may be inspected, and means on the address side to give one compartment the appearance of having been open to receive its contents and thereafter sealed when the envelope is ready to be deposited in the mails, substantially as shown and described.

8. An envelope structure as specified in claim 2, said compartment which has the appearance of being sealed on the face of the envelope being open at an edge thereof.

9. An envelope structure as specified in claim 2, having a place for the address within the area of the apparently sealed com-

partment, and the envelope having an opening concealed inside thereof to afford access to the apparently sealed compartment.

10. A duplex mailing envelope comprising a plurality of compartments one of 70 which has the appearance on the face of the envelope of having been open and thereafter sealed when the envelope is ready to be deposited in the mails, but all of which compartments are open for inspection of the 75 contents thereof, said compartment which has the appearance of being sealed on the face of the envelope being open at an edge thereof inside of the envelope.

11. A duplex mailing envelope comprising a plurality of compartments one of 80 which has the appearance on the face of the envelope of being sealed and all of which compartments are open for inspection of the 85 contents thereof, said apparently sealed compartment being located on the address side of the envelope, with a place for the address within the area of the apparently sealed compartment, and the envelope having a loose flap at one end which can be 90 pulled out to afford access to the apparently sealed compartment.

12. A duplex mailing envelope comprising a plurality of compartments one of 95 which has the appearance on the face of the envelope of being sealed and all of which compartments are open for inspection of the contents thereof, said apparently sealed compartment being smaller than the other compartment, and this smaller compartment 100 being formed by the front wall of the envelope and by a smaller inner wall, so that the smaller compartment is within the area of the larger compartment, and having a flap on the front of the envelope to give said 105 smaller compartment the appearance of being sealed, with the place for the address below said flap, and means at one end of the envelope to afford access to both compartments, so that matter less than first class 110 may be enclosed in each compartment.

13. A duplex mailing envelope comprising, when ready for the mails, a plurality of compartments one of which has the appearance of having been open on the face of the envelope to receive the contents thereof, and of being sealed, and all of which compartments are open for inspection of the 115 contents thereof, said compartment which has the appearance of being sealed on the 120 face of the envelope being open at an edge thereof.

14. A duplex mailing envelope comprising a plurality of compartments one of 125 which has the appearance on the face of the envelope of being sealed and all of which compartments are open for inspection of the contents thereof, said apparently sealed compartment being smaller than the other compartment, being formed by a sheet 130

which is loose at an edge thereof inside the envelope, thereby to form a concealed opening for inspection of the contents of the smaller compartment, and the smaller compartment being located on the address side of the envelope, said smaller compartment having a sealing flap for its upper edge, which flap gives the smaller compartment the appearance of being entirely sealed, and an address space being provided below said flap.

15. A duplex mailing envelope comprising a plurality of compartments one of which has the appearance on the face of the envelope of being sealed and all of which compartments are open for inspection of the contents thereof, said apparently sealed compartment being located within the envelope and on the address side thereof, with a place for the address within the area of the apparently sealed compartment, and the envelope having a loose flap at one end which can be pulled out to afford access to the apparently sealed compartment, one edge of the smaller compartment being left loose for this purpose.

16. A duplex mailing envelope comprising a plurality of compartments one of which has the appearance of being sealed and all of which compartments are open for inspection of the contents thereof, the front wall of the envelope having a slot, said apparently sealed compartment being smaller than the other compartment, and this smaller compartment being formed by the front wall of the envelope and by a smaller inner wall, so that the smaller compartment is within the area of the larger compartment, and having a flap formed integral with said inner wall and extending through

said slot to give said smaller compartment 40 the appearance of being sealed on the face of the envelope, with the place for the address below said flap, and means at one end of the envelope to afford access to both compartments, so that matter less than first 45 class may be enclosed in each compartment.

17. A duplex mailing envelope comprising a plurality of compartments one of which has the appearance on the face of the envelope of being sealed and all of which 50 compartments are open for inspection of the contents thereof, said apparently sealed compartment being indicated on the address side of the envelope, with a place for the address within the area of the apparently sealed compartment, and the envelope having means to afford access to the apparently sealed compartment.

18. A duplex mailing envelope comprising a plurality of compartments one of 60 which is open at one point only for inspection of the contents thereof, before the envelope is ready to be deposited in the mails, and another of which compartments is open at two places, together with means for sealing this other compartment at one open place, whereby the contents of both compartments are accessible when the envelope 65 is ready to be deposited in the mails.

19. A duplex envelope comprising a plurality of compartments one of which is really left open for inspection of the contents thereof, when the envelope is ready to be deposited in the mails, but having means on the address side of the envelope 75 to simulate a sealed compartment.

JOSEPH SAWDON.
